Fig. 3

Fig. 4

Fig. 5

FIG. 1 is a view in perspective of a child's riding toy, showing my new design;

FIG. 2 is a top plan view thereof;

FIG. 3 is an elevational view of the side opposite that illustrated in FIG. 1;

FIG. 4 is a front elevational view thereof; and

FIG. 5 is a rear elevational view thereof.

I claim:

The ornamental design for a child's riding toy, substantially as shown.
